HONE

Robert E. Brown, Olean, N. Y.; Ethel I. Brown
administratrix of said Robert E. Brown, deceased

Application May 3, 1933, Serial No. 669,265
Renewed July 6, 1934

12 Claims. (Cl. 51—211)

This invention relates to blade sharpeners and more particularly to a novel form of hone especially designed for sharpening either single or double edged razor blades.

5 Heretofore, hones have been constructed with a concave abrading surface struck from a fixed center so that a low point is present at the bottom of the abrading surface which must be spanned or bridged by a razor blade when the 10 blade is placed in position on the hone preparatory to sharpening the same. The placing of the blade on such a concave abrading surface causes the extreme delicate cutting edge or edges of the blade to come in instant and positive abrading contact with the hone and as the 15 inclination of the abrading surface at said low point does not always coincide with the bevel or inclination of the cutting edge of the blade the delicate adjustment of said cutting edge is often 20 damaged and some times ruined. The careless positioning of the razor blade on the concave abrading surface often results in similar damage to the cutting edge of the blades. Furthermore, when the hone is provided with a continuous 25 uniform concave abrading surface, the last movement of the blade when sharpening double edged blades is necessarily a honing stroke on one of the edges whereas in order to obtain the best results the last movement of the blade should be a 30 stropping or back-first stroke.

In order to overcome these difficulties I have provided a hone having oppositely disposed concave abrading surfaces struck from different centers but having the same radii, said concave surfaces being connected by a flat blade support or platform disposed tangentially thereto so that the blade may be easily and gently moved laterally onto either abrading surface without liability of damage to the delicate cutting edge.

40 The invention contemplates the provision of a flat horizontally disposed blade supporting surface or platform of a width equal to at least the width of a razor blade so that when the blade is positioned on the platform neither cutting edge will come in direct or positive contact with either abrading surface and liability of damage to the delicate cutting edge of the blade due to 45 careless placing of the blade on the hone thus effectually obviated.

The invention further aims to provide a hone having concave abrading surfaces each of which is provided with distinctive zones or areas of relatively fine and coarse abrading material so 50 that a blade may be first thoroughly ground,

when necessary, and then honed to impart a smooth shaving edge thereto.

A still further object of the invention is generally to improve this class of devices so as to increase their durability, utility and efficiency. 5

In the accompanying drawing forming a part of this specification and in which like reference numerals indicate corresponding parts in all the figures of the drawing:

Figure 1 is a perspective view of a hone embodying the present invention. 10

Figure 2 is an end elevation on an enlarged scale, showing in full lines a razor blade resting on the supporting platform and in dotted lines the position assumed by the blade when making 15 an initial sharpening stroke.

Figure 3 is a detail end elevation illustrating a modified form of the invention.

Figure 4 is a similar view illustrating another 20 modification.

Figure 5 is an end elevation illustrating a further modification. 25

The improved hone forming the subject matter of the present invention comprises a block or slab 5 preferably substantially rectangular in shape, 25 as shown, and molded or otherwise formed of suitable abrasive material. The block is preferably provided with a flat base or bottom 6 so that it may rest firmly on a table or other support during the sharpening operation. 30

Formed in the block or slab and opening through the upper face and opposite sides thereof are coacting concave abrading surfaces 7 and 8 having the same radii, as indicated by the dotted lines 9, but struck from different centers, as 35 indicated at 10, and over which the razor blade 10' travels in the act of sharpening the same. The concave abrading surfaces 7 and 8 may be in the form of segments of any correct sized circle which may be required to properly fit the angle at the 40 extreme edge of the razor blade at which said edge has been ground, honed, or otherwise sharpened.

Disposed between the concave abrading surfaces 7 and 8 is an intermediate horizontally disposed blade supporting surface 11 on which the 45 blade 10' is adapted to rest when in position on the hone. The supporting surface 11 is preferably slightly wider than the widest razor blade and is disposed at a tangent to the abrading surfaces 7 and 8 so that said abrading surfaces will 50 merge into the supporting surface and not present any angles or obstruction at the junction thereof and will thus allow the edges of the blade to positively and gently contact with the abrading surfaces when the blade is moved laterally on the 55

platform in the direction of either abrading surface. The curvature of the abrading surfaces 7 and 8 is such that were the blade supporting surface removed and the adjacent ends of the abrading surfaces brought in contact with each other, said surfaces would form the lower segment of a perfect circle.

In using the hone, the blade to be sharpened is positioned on the supporting surface 11 with one or two fingers of the hand resting upon the blade and a reciprocating motion imparted thereto. At this point it may be noted that inasmuch as the supporting surface 11 is flat and of greater width than the width of the razor blade and is disposed at a tangent to the abrading surfaces, when said blade is positioned on the supporting surface 11, the delicate cutting edges of the blade will not come in contact with the abrading surfaces and turn or otherwise damage the shaving edge. As the blade is reciprocated to effect the sharpening thereof the initial forward movement of the blade in one direction will cause the cutting edge of the blade to gently come in contact with the adjacent abrading surface and impart a honing action thereto and a reverse or backward movement of the blade will give the cutting edge a stropping action. Inasmuch as one side of the blade always rests on the supporting surface 11 it follows that the last stroke of the blade in sharpening the same will be a stropping stroke and not a honing stroke, which is quite a desideratum in the sharpening of all kinds of razor blades. Furthermore, as the blade initially rests on the supporting surface 11, it may be placed thereon in a careless manner without liability of damaging the shaving edge, this being due to the fact that the supporting surface 11 is perfectly flat and of a width greater than the width of the blade. As the flat supporting surface 11 is disposed at a tangent to the abrading surfaces and gradually merges into said surfaces, it follows that I am able to attain the most delicate contact between the extreme edge of the blade and the abrading surfaces and, consequently, damage to the delicate shaving edge is effectually obviated. This positive yet delicate contact between the shaving edge and the abrading surfaces is of paramount importance as is likewise the fact that the last movement of the blade imparts a stropping action thereto as contradistinguished to a honing action. The rearward or stropping action of the blade tends to align the tooth-like unevenness of the shaving edge and is particularly effective in the instant case owing to the fact that the abrading surface is extremely fine and the stropped edge gradually and gently leaves contact with said abrading surface. This makes for the highest degree of shaving edge perfection and is impossible of accomplishment with the ordinary concave hone.

In Figure 3 of the drawing there is illustrated a modified form of the invention in which the lower portion of the hone is formed of relatively fine abrading material and the upper portion 12 formed of coarser material, the purpose of the coarser material 12 being to enable the user to cut down the edges of razor blades rapidly if said blades should be rusty or very dull, by merely continuing the motion of the blade up to and across the curved face of the coarser zone of the hone. It will, of course, be understood that after the rust has been removed by contact with the coarse zone of the blade sharpened thereon, the honing action will be continued on the lower fine zone of the hone in the usual manner so as to give the blade a smooth sharp shaving edge.

Another modification of the invention is illustrated in Figure 4, in which the hone is provided with upper and lower abrading surfaces 13 and 14 which may be of the same or different curvatures and one of said abrading surfaces may be formed with transverse corrugations 15 or otherwise roughened to serve the same purpose as the coarse abrading portion illustrated in Figure 3 of the drawing. If desired, however, the corrugations or roughened portion may be formed on the intermediate blade supporting surface instead of on the concave surfaces.

It has been found by actual experience that a hone constructed with a concave abrading surface of fixed or constant curvature will not give the desired results as when a blade is placed in the bottom of the concave it must necessarily span or bridge the low point of said concave and the initial movement of the blade in either direction will have a tendency to turn or damage the delicate cutting edge due to the fact that the inclination of the concave walls does not always coincide with the inclination or bevel of the cutting edge of the blade and that when positioning the blade at the low point of the concavity, the concave surface on either side of the low point of the concave also tends to damage the delicate cutting edge. With the present invention this damaging action to the delicate cutting edge of the blade cannot occur as the blade slides from the supporting surface into edge abrading contact with the hone so that the most careless or inexperienced person can effectively sharpen razor blades with my hone without liability of damaging the delicate shaving edge and also be assured of true alining of the tooth-like unevenness of said shaving edge as the last movement of the blade on the abrading surface is a stropping stroke and not a honing stroke.

In Figure 5, I have illustrated a further modification in which the central portion of the hone is provided with a convex blade supporting surface 16 of the desired width, instead of a flat surface, this form of the device being particularly adapted for sharpening barber razors as a convex surface will take such a razor without damaging the cutting edge thereof. It will be noted that regardless of whether the intermediate supporting surface is flat or convex, said surface will receive and support a razor blade thereon with the cutting edge or edges of the blade normally out of abrading contact with the concave surfaces so as to prevent damage to the cutting edge of the blade.

It will, of course, be understood that the hones may be made in different sizes and shapes and constructed from any suitable material having the desired abrading or stropping properties without departing from the spirit of the invention.

Having thus described the invention, what I claim is:

1. A hone having a concave abrading surface, and a blade supporting surface tangential thereto.
2. A hone having concave abrading surfaces, and a blade supporting surface between the abrading surfaces and tangential thereto.
3. A hone having concave abrading surfaces, and a flat horizontal blade supporting surface between the abrading surfaces and tangential thereto.
4. A hone having concave abrading surfaces, and a blade supporting surface between and tangential to the abrading surfaces and of a width approximately equal to the width of a razor blade.

5. A hone having concave surfaces each of which is provided with distinctive areas of relatively fine and coarse abrading material, and a blade supporting surface between the areas of fine abrading material and tangential thereto. 5
6. A hone comprising a slab having concave abrading surfaces opening through the top thereof, and a flat blade supporting surface between the abrading surfaces and tangential thereto. 10
7. A hone provided with concave abrading surfaces struck from different centers but having the same radii, and a flat blade supporting surface connecting the abrading surfaces and tangential thereto. 10
8. A hone comprising a slab of abrading material having concave abrading surfaces therein and opening through the top thereof, and a flat horizontally disposed blade supporting surface connecting the abrading surfaces and tangential thereto. 15
9. A hone comprising a slab of abrading material having one face thereof provided with concave abrading surfaces struck from different centers but having the same radii, and a flat horizontal surface of a width sufficient to support a razor blade thereon connecting the concave abrading surfaces and gradually merging into said concave surfaces. 20
10. A hone comprising a substantially rectangular slab of abrading material having a concave portion opening through the top and opposite sides thereof and presenting oppositely disposed concave abrading surfaces struck from different centers but having the same radii, and a flat horizontally disposed supporting surface of greater width than a razor blade connecting the inner ends of the concave abrading surfaces and disposed tangentially thereto. 25
11. A hone comprising a body portion having oppositely disposed concave abrading surfaces and a flat intermediate horizontal blade supporting surface merging into and connecting the concave abrading surfaces and disposed tangential thereto whereby a blade resting on the supporting surface may be moved laterally from said supporting surface to bring the cutting edge of said blade into direct and positive contact with either abrading surface. 15
12. A hone having concave abrading surfaces and a supporting surface between the abrading surfaces adapted to receive and support a razor blade thereon with the cutting edges of the blade normally out of abrading contact with said concave surfaces. 20
